UNITED STATES PATENT OFFICE.

SAMUEL N. McCLEAN, OF DETROIT, MICHIGAN.

CLOTHES WRINGER.

Application filed July 26, 1920. Serial No. 398,933.

This invention relates to clothes wringers and has for its object to improve and simplify the design, construction, operation, and manufacture of the wringer; to provide a wringer embodying mechanism which effectively controls the adjustment, operation, and functioning of the wringer rolls and their driving means, the drip controlling means, and the roll pressure and power releasing means; to provide a wringer so constructed that the tension, operation, and pressure of the rolls may be adapted to any required and varying pressure or feeding action of the clothes which pass between the rolls; to provide driving means to continuously drive both the upper and lower rolls with the required pressure for both light and heavy clothing, and a safety device which simultaneously releases both the rolls and the power and simultaneously throws both the power and the tension of the rolls either on or off, and to control the flow of the drip in the required direction.

A further object is to provide an improved wringer so designed and constructed that it may be formed of separable pressed steel halves or parts and rapidly manufactured and produced with little machinery and at small expense, and to obtain certain advantages and improvements in the manufacture, operation, and use of the wringer, as hereinafter set forth.

The invention comprises the construction and arrangement of parts hereinafter described and claimed.

Referring to the accompanying drawings, which are hereby made part of this specification, Fig. 1 is a side view of my automatic wringer with the near side wall removed, showing the operating parts partly in section and partly in elevation; Fig. 2 is a sectional plan view on the line 2—2, Fig. 1; Fig. 3 is a detail section on the line 3—3, Fig. 1;

Fig. 4 is a broken outside elevation of Fig. 1, showing the releasing means, tension lever and also illustrating drip controlling means; Fig. 5 is a sectional elevation on the line 5—5, Fig. 4, showing the drip controlling means; Fig. 6 is a sectional view on the line 6—6, Fig. 4 showing the driving gearing in elevation; and Fig. 7 illustrates a modification.

My invention may be briefly described as an automatic wringer constructed with com-

panion opposing rolls, a floating spring connected with the opposite ends of one of the rolls to automatically and operatively control, adjust, and release the tension, driving means connecting the driving and driven rolls for continuously driving the rolls in the right direction and for controlling the various movements of the rolls, said wringer being constructed with releasing and tension controlling means which simultaneously releases the rolls and cuts out the power and throws in the power and applies and adjusts the tension to the rolls, and being provided with drip controlling means which directs the flow of the drip in the right direction.

Referring to Fig. 1 in the accompanying drawings, 1 is the pressed steel frame of the wringer, which is formed by suitable dies in separable halves or parts, which are removably held together by the screw-threaded stud-bolts and nuts 2. This pressed steel frame 1 may be of any required shape to permit it to receive and operatively and removably retain the rolls and their associated driving and controlling means.

The frame 1 of the wringer is shown fixedly connected with a swinging wringer bracket to which it is attached by the cross-bolts as illustrated at 4. The bracket 3 forms a sleeve about a fixed part 5 by which it is attached to a suitable washing tub or washing machine, and about which it may be rotatably adjusted and locked in any position by the latch 5.

The invention may be constructed and operated either as a hand wringer with the usual hand crank, not shown, or as a power driven wringer as shown in the drawings. The power shaft 6 is operatively carried in the fixed part of the bracket 5 and is suitably connected with the wringer drive-shaft 7, such as by a bevel gear 8 which is carried on the upper end of the shaft 6 and two bevel gears 9 carried on the wringer shaft 7. These gears are removably carried in the bracket 3 to permit them to be assembled and removed from the power-shaft 6 which may be connected with any suitable type of driving means or motor. The double-ended clutch 10 which is carried on the shaft 7 between the pinions 9 may be shifted to either of its end positions or to the neutral position by an operating arm 11 on a shaft 12 having an operating handle 13 on the out-

side of the casing, the purpose of said clutch being to drive the wringer in the forward or reverse direction or stop it, as desired.

The lower wringer roll 14 is coupled to the 5 upper wringer roll 15, which upper roll has rotating, oscillating and reciprocating movement in the frame.

The tension device comprises a floating spring 16 located in a cylindrical or tubular 10 part 1^a of the frame 1 and has floating connection with the opposite ends of the roll 15 by means of cables 17 and 18. These cables are attached to opposite ends of the spring 16 to cause it to exert floating tension upon 15 the opposite ends of the roll 15 and to automatically control and adjust the tension between the rolls 14, 15.

The spring 16 is preferably a compression spring and carries at its opposite ends the 20 companion caps 19 which carry the pulleys 20, 21. These caps are movable in the tube 1^a and receive the end pressure of the spring 16.

The cable 17 is connected with a bushing 25 22 on one end, say the left hand end, Fig. 1 of the roll 15 and passes over a stationary pulley 23 which is journaled on one end of a bolt 2. The cable then passes through to the opposite end of the spring 16 around the 30 pulley 21, is then returned to a second stationary pulley 23^a and passes around this pulley and up at the side of the frame to the tension lever 24.

The cable 18 is connected with a similar 35 bushing at the opposite end of the roll 15 and passes around a stationary pulley 25 which is carried on a stud 2 as before at the right-hand side of the frame. It then passes diagonally through the spring 16 and 40 around the pulley 20 and is returned to and passes over a second stationary pulley 25^a and passes diagonally through the spring 16 to a stationary pulley 26 which is also carried on the bolt 2 at the left-hand side of 45 the frame, and from this pulley 26 it passes up and is attached to the tension lever 24. It is thus apparent that the spring 16 floats between the opposite ends of the roll 15 and the tension lever 24.

50 The tension lever 24 is on a shaft 27 provided with an outside operating arm 28 (Fig. 4), and the arm 24 is provided with a hub part 29 which is formed with ratchet teeth 30 with which the spring-pressed pawl 31 engages to lock or release the tension lever. This pawl 31 is pivotally carried in the frame and is actuated by the coiled spring 32 and is provided with a lug 33 which extends into the path of a lug 34 on 60 a releasing slide 35.

A spring-pressed clutch sleeve 36 is operatively slidable on the shaft 7 and a notch 37 therein engages with a pin 38. Shaft 7 is formed in two parts, one of which connects with the roll and the other with the

drive, and the sleeve 36 is connected with the driving portion of the shaft by means of the pin and slot 39 to control the throwing in and throwing out of the power.

The releasing bar or slide 35 is constructed near its lower part with the cam lug 40 which engages with the sleeve 36 to throw back the sleeve against the pressure of the spring 41 and release the clutch at the time that the lug 34 engages with the pawl 31 both to release the rolls and throw out the power simultaneously. The releasing bar 35 is moved in one direction by pressing down upon its handle 42 with the hand, or automatically, as will appear hereafter, and is lifted or restored to normal position by a light spring 43.

An automatic releasing lever 44 is pivotally carried in the frame and at one end is pivotally connected to the bar 35. This lever is provided with an inwardly projecting arm 45 which extends into the path of upward movement of an arm 46 carried by the roll 15, which arm strikes the lever arm 45 to automatically depress the bar 35 to both release the rolls and throw out the power in case the operator's hand is drawn between the rolls or when the work is too thick. In other words if the roll 15 is lifted to its limit it automatically releases or disconnects both the pressure and drive.

Figs. 4 and 5 also show the drip board 47, which includes a sleeve 47^a formed to fit around the tubular or cylindrical part 1^a of the wringer frame and is provided with laterally extending drip deflecting wings 48 and is rotated or oscillated on the tubular part of the frame to cause the wings to alternately extend on the opposite sides of the wringer.

An auxiliary drip-shield 49 extends partially around the roll 14 and between it and the primary drip-board 47. This drip-shield 49 is formed at its opposite ends with projecting arms 50 which are pivoted on the shaft 7. The auxiliary shield is connected with the primary drip-board 47 by the crossed cables or straps 51, 52, these straps operating, when the primary drip-board is tilted in one direction, to tilt the auxiliary drip-shield in the reverse direction, causing the suds to flow beneath and across from the opposite side of the roll 14 in the required direction.

Fig. 7 illustrates the drip-board and auxiliary drip-screen constructed with two segmental gears 53, 54, which engage with each other to swing the drip-shield 49 to the reverse or opposite side of the roll 14.

In Fig. 4 I have shown the drip-board 47 constructed with a laterally projecting arm 80 and connecting rod 81 by which it is connected with the wringer reversing lever 13 for controlling the forward and reverse action of the wringer directly from the drip

controlling means, thus controlling the flow of the drip in the required direction in which the rolls are running.

In Fig. 6 I have shown a preferred form 5 of wringer driving gears in which a train of gears is used to drive both the upper and lower rolls in any required position and operation of the rolls. Such an arrangement is used at both ends of the wringer. In this 10 construction the gears 55 are carried at the opposite ends of the roll 14 on the shaft 7 and are keyed to this shaft and turn with it. These gears 55 engage with the gears 56 by means of the link connection 57 and 15 the gears 56 engage with the gears 58 by the link connection 57a.

The gears 59 are carried on the opposite ends of the shaft of the wringer roll 15 and are fixedly connected to rotate with this 20 shaft. These gears 59 are connected with the gears 58 by the connecting link 60. The gears 58 do not mesh with the gears 55 and gears 55 and 59 run in the reverse direction, causing the rolls 14 and 15 to feed the clothing in a common direction in either the forward or reverse action of the rolls and causing the rolls to act together both when they 25 are close together or far apart, or at any intermediate or possible relative position of 30 the rolls.

The functioning of the wringer rolls and the combination and control of the train of wringer driving gears are controlled by the lever 61 and the connecting bar 62 as fol- 35 lows:

The lever 61 is pivoted to the frame of the machine by the pivot and slot 63 and is connected to the shaft 64 of the gear 56 and the other end of the lever 61 is connected 40 with the bar 62 by the pivot 65. The other end of the bar 62 connects with the gear 59 and roll 15 by means of the pivot shaft 66 and the shaft or pivot 66 at its opposite ends extends into a vertical slot or guideway 45 67 which is formed in the frame of the machine at the opposite ends of the roll 15.

In the operation of the rolls 14, 15, it is thus apparent that when the rolls are drawn together by the tension of the spring 16 and 50 the wringer is operated to carry the clothing between the rolls, the roll 14 rotates in a fixed position and the roll 15 is moved against the pressure of the spring, causing the connecting link 62 to draw the end of 55 the lever 61 and lift or swing the gears 56, 58 up at about one-half the speed of the upward movement of the gears 59, maintaining a correct relation and meshing and driving 60 action of the train of gears and driving both the upper and lower rolls and allowing the upper roll to vibrate and oscillate freely with the varying thickness of the clothing as it passes between the rolls. The slot 67 guides the reciprocating movement of the 65 upper roll and permits its reciprocating

movement at either end of the roll, there being a sufficient clearance in the gear teeth and connections to permit the adjusting and oscillating movement of the rolls.

The tension lever 24 is controlled by 70 means of the set screw and lock nut 68 which engages with the lever 24 to limit its movement but which may be adjusted to permit an additional movement of this lever for taking up the stretch of the cables 75 and the wear of the rolls.

The releasing bar 35 is provided at its lower end with a laterally projecting pin 69 which extends into the path of a cam lug 69a on an arm 69b of the tension lever 80 24 and which pin is actuated to cause the lug 34 to engage the pawl 31 to release the cam lug 40 from engagement with the rim of the sleeve 36.

In Figs. 4 and 5 I have also shown 85 shields, 71 and 72 placed at the opposite sides of the driving roll 14 and connected with the frame to permit the clothing to be thrown against the upper roll and above the top of the shields, the action of the upper 90 roll and gravity operating to carry the clothing between the rolls, and the shields forming a protection in the operation of feeding the clothing.

A spring-pressed latch 73 is preferably 95 hinged to the under side of the wing 48 of the drip-board 47 and engages with the hole 74 to lock and release the drip-board when the wringer is driven in one direction and with the hole 75 to drive the wringer in 100 the reverse direction and with the hole 76 to hold the drip-boards neutral.

The operation of the invention has been set forth in connection with the description of its parts, and the operation of the invention 105 as a whole may be briefly stated as follows.

When the wringer is not in use, the releasing bar 35 is struck down to release the tension lever and the spring 16 then expands and the caps 19 engage the pulleys 23, 25, thus entirely removing the tension of the spring from the upper roll and permitting the rolls to separate to their full movement of an inch or an inch-and-a-half. 110 In case of accident this operation throws back the sleeve 36 and throws out the power, by reason of the pin 38 on the roll shaft 14 being disengaged from the sleeve 36, releases the rolls, and permits the finger, hand, or 115 clothing to be readily withdrawn from between the rolls.

When it is desired to use the wringer, the tension lever 24 is swung back to the position shown in Fig. 1, by the operation of the arm 28, bringing the lug 69a into engagement with the pin 69, releasing the bar 35 and permitting the latch 31 to reengage with the rack teeth 30 and draw the pulleys 20, 21, against the opposite ends of the 120

spring 16 causing the spring to float and exert its tension upon opposite ends of the roll 15 and maintain an equal pressure and tension on the opposite ends of this roll.

5 The wringer is then started for operating the machine by pulling the drip-board up to one side, as shown in Fig. 5, and throwing in the driving clutch to drive the wringer in one direction, causing the suds and drip 10 to flow back into the tub out of which the clothes are being wrung. When the drip-board is swung to its reverse position and the rolls are reversed the flow of the drip and the suds is in the opposite direction 15 and again into the tub from which the clothes are being wrung.

The tension of the spring 16 is set when the rolls are in contact at the tension required for the wringing of light clothing, 20 and the spring 16 is constructed so that the tension will increase with the thickness of the clothing, and the rolls will separate freely and uniformly at the required tension for the heaviest bed-quilts and articles to 25 be passed between the rolls, the upper roll having a travel sufficient to adapt it to the largest garments or bed-quilts without reaching the full limit of its travel. The spring 16 therefore never normally reaches 30 the full limit of its travel and works at its intermediate compression. When the roll 15 has reached nearly the limit of its travel and has opened to an amount greater than is required for bed-quilts and the largest 35 articles to be wrung, the arm 46 strikes the lever 45 and releases the rolls and throws out the power.

The tension of the spring 16 being less than the driving power of the motor and the clearance between the rolls and the travel of the rolls being greater than that required for the thickest garments, the danger of jamming the rolls is greatly reduced and the feeding and wringing of the garments 45 made easier and more uniform.

The operation and automatic control of the train of gears which engages with the opposite ends of the upper and lower rolls controls and permits a reciprocating and 50 rotating action of the rolls and, in combination with the automatic action and function of the floating spring 16 operates to greatly increase the efficiency and automatic function of the wringer.

55 Having now fully described my invention and its mode of operation, what I claim as my invention and desire to secure by Letters Patent of the United States is as follows:

60 1. A clothes wringer provided with companion opposing rolls, a floating spring, and means including cable and sheave mechanism for operatively connecting said spring with the opposite ends of one of the rolls so as to automatically adjust the tension between said rolls.

2. A clothes wringer provided with relatively separable companion rolls, driving means connected with the rolls, and a compression floating spring carried by the wringer and having a flexible connection 70 with the opposite ends of one of the rolls so as to automatically adjust the tension between said rolls.

3. A clothes wringer provided with companion relatively movable rolls, driving 75 means connected with one of the rolls, a train of four gears, one end of the train operatively connected with the driving roll and the other end of the train operatively connected with the driven roll, links connecting said gears, and a lever connection between the driven roll gear and one of the intermediate gears and having a loose pivotal bearing in the frame.

4. A clothes wringer provided with a pair 80 of driving and driven relatively movable rolls, a floating spring connected with the opposite ends of the driven roll for automatically regulating the tension between said rolls, means for latching said spring under tension and releasing the same, and means tending to normally return said latching means to latching position.

5. A clothes wringer provided with relatively movable rolls, a floating compression 85 spring connected with the opposite ends of one of the rolls to automatically regulate the tension between said rolls, a tension lever operatively connected with the spring, and releasing means operatively connected with the tension lever.

6. A clothes wringer provided with a pair of rolls, a floating spring connected with the opposite ends of one of the rolls to automatically regulate the tension between said rolls, 105 a tension lever operatively connected with the spring, releasing means operatively engaging with the tension lever, and driving means operatively connected with one of the rolls and with a source of power, said driving means being adapted for engagement with the releasing means to release the tension between said rolls and to disconnect said driving means from said source of power.

7. A clothes wringer provided with a pair of rolls, a floating spring connected with the opposite ends of one of the rolls to automatically regulate the tension between said rolls, a tension lever operatively connected 120 with the spring, and an adjustable stop means engaging with the tension lever.

8. A clothes wringer provided with a pair of rolls, a floating spring connected with the opposite ends of one of the rolls to automatically regulate the tension between said rolls, a tension applying lever operatively connected with the spring, adjusting means engaging with the tension lever, and releasing means engaging with the tension lever.

9. A clothes wringer provided with a pair of rolls, a spring attached by flexible connections to the opposite ends of one of the rolls to automatically regulate the tension
5 between said rolls, and means engaging with one of the rolls for automatically releasing the tension between said rolls.
10. A clothes wringer provided with a pair of rolls, a floating spring connected
10 with the opposite ends of one of the rolls to automatically regulate the tension between said rolls, a tension lever operatively connected with the spring, manually operable releasing means operatively connected with
15 the tension lever, and an automatic releasing means operatively connected with the tension lever and engaging with the movable roll.
11. A clothes wringer provided with a
20 pair of companion rolls, a wringer frame carrying the rolls and having a cylindrical part formed beneath the rolls, a drip-board movable around the cylindrical part of the frame as a bearing support therefor, a floating spring carried within the cylindrical part of the frame and connected with the
25
- opposite ends of the upper roll for automatically regulating the tension between said rolls, and driving means connected with the lower roll. 30
12. A clothes wringer provided with a driving and a driven roll, a frame operatively retaining the rolls and provided with a tubular part beneath the driving roll, a floating spring carried in the tubular part
35 of the frame and operatively connected with the opposite ends of the upper roll to automatically regulate the tension between said rolls, a drip-board having a limited movement around the tubular part of the frame
40 as a bearing support therefor, an auxiliary drip-board formed between the lower roll and the primary drip-board and provided with upwardly projecting arms at its opposite ends and carried on the shaft of the
45 lower roll, means operatively connecting the upper and lower drip-boards for swinging them in opposite directions, and driving means connected with the lower roll. 45
- In testimony whereof I hereby affix my signature. 50

SAMUEL N. McCLEAN.
